CLAIM

The ornamental design for a square pan, as shown and described.

DESCRIPTION

FIG. 1 is a top, front, right side perspective view of a square pan showing the new design;

FIG. 2 is a front elevation view thereof;

FIG. 3 is a right side elevation view thereof;

FIG. 4 is a top plan view thereof; and,

FIG. 5 is a bottom plan view thereof.

The broken lines in the drawings depict portions of the baking sheet that form no part of the claimed design.

1 Claim, 2 Drawing Sheets(56)
